UNITED STATES PATENT OFFICE

SAMUEL MARCUS, OF RIVERDALE, NEW YORK, ASSIGNOR TO MARKON MANUFACTURING CO., INC., OF NEW YORK, N. Y., A CORPORATION OF NEW YORK

EYE SET

Application filed August 28, 1928. Serial No. 302,549.

This invention relates to an eye set, and a particular object of the invention is to provide an eye set embodying a novel and efficient carrier portion by which the eyes proper are supported within the head.

A more detailed object is to provide a carrier which is of simple design, which may be readily and cheaply manufactured, which may be quickly and easily operated for attaching the eye set within a doll head, and which will function to properly and efficiently support the eyes within the head.

A further and more specific purpose of the present improvement is to provide a carrier which is adapted to be mounted preferably in a vertical position within a head and which has widely spaced end portions co-operative with prepared parts of the head for determining the position of the eye set within the head and for fastening it there.

A further detailed object is to provide an eye set comprising a carrier having means for temporarily retaining the carrier in position within a doll head and having other means for permanently retaining it within the doll head.

A further detailed object is to provide an eye set comprising a carrier having movable attaching devices thereon for permanently attaching the carrier within a doll head, and to provide a carrier with means to be impaled within the material of the head to temporarily retain the carrier in a selected position during the movement of said attaching devices.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:

Fig. 1 is a vertical sectional view through

a doll head having an eye set therein in accordance with this invention.

Fig. 2 is a vertical sectional view taken substantially upon the plane of line II—II of Fig. 1.

Fig. 3 is an enlarged sectional view taken upon the plane of line III—III of Fig. 1, and

Fig. 4 is a perspective view showing the several parts of the carrier in detached relation.

Referring to the drawings for describing in detail the structure illustrated therein, the reference character L indicates a doll head having the usual eye openings as 1 and 2 in its front wall.

The eye set includes the usual eye balls as 3 and 4. These may be connected with the carrier by any appropriate means but for convenience are here shown as being arranged at opposite ends of a cross rod 5 which is received through bearings 6—7 provided in a pair of arms as 8—9 which project forwardly from the mid-portion of the carrier, and particularly from the body member 10 of the carrier.

The cross rod may preferably be yieldingly supported by the arms 8—9 by making the bearings 6—7 elongated as shown and providing a light spring, or springs, as 11, for bearing against the side of the cross rod to urge the cross rod forwardly and hence to hold the eye balls in light frictional contact with the rearwardly facing concaved surfaces 12 of the eye openings, it being understood that in use the carrier is stationary within the head and that the slotted bearings 6—7 may be sufficiently long so that the cross rod will at no time engage the outer or forward ends of said bearings in normal use.

A laterally extending arm as 13 may be connected with the cross rod, preferably at a point mid-way between the arms 8 and 9, and may depend from the cross rod to carry a weight as 14 for causing a gravity controlled relative oscillatory movement of the eyes when the doll is moved between upright and reclining positions, as will be readily understood.

The body member of the carrier may be

formed with a central opening as 15 there-through for accommodating passage and movement of the arm 13 between two extremes, the movement of the arm 13 to eye opening position being limited by engagement of the weight with a surface portion as 16 of the head, and the movement of said arm to eye closing position being limited by engagement of said arm with a spring finger as 17 which may be conveniently provided from the material struck out from the body in the formation of the opening 15.

The body member of the carrier is suitably elongated so that it extends across the region of the eyes and has its opposite ends adjacent to opposite wall parts of the head either horizontally or vertically as may be preferred, the vertical arrangement being however herein shown and specifically described.

In addition to the parts already referred to, the carrier comprises a pair of attaching members as 18 and 19 one arranged at one end of the carrier and the other at the opposite end of the carrier. In the instance illustrated these are of substantially identical form and consist each of a main portion 20 having turned over edges to provide guideways as 21 and 22 thereon parallel to each other and arranged to receive co-operative guide parts as 23-24 provided upon the body 10.

At one end each attaching member is shaped to provide one or more prongs or tangs as 25 projecting therefrom in the general direction of length of the carrier and adapted, when the attaching members are slid outwardly along the body in use to be thrust into the material of the doll head, substantially as indicated, for thereby rigidly connecting the carrier to the head.

The turned over edges of the attaching members provide end edge wall surfaces as 26-26 adjacent the tangs 25 for abutting against the opposing wall surfaces as 27-27 of the head for limiting the distance to which the tangs may be thrust into the material of the head.

Each attaching member is preferably provided with laterally projecting lugs as 28-28 thereon constituting means to be gripped by a tool of appropriate construction for forcing the attaching members slidably along the body both to and from attaching position.

The fit of the attaching members on to the body, that is the fit of the interengaging guide-way parts 21-22 and 23-24, is intended to be sufficiently tight so that while movement of the attaching members longitudinally of the body is possible when force is applied as by means of a tool as suggested, there will be no likelihood of any relative movement of the attaching members upon the body at any other time. Once the attaching members have been driven to attaching position they will remain in that position

and hold the carrier rigidly connected with the head at all times thereafter unless force is again applied to move them out of engagement with the head.

The body member 10 of the carrier is preferably of U shape in cross section and the guide parts 23-24 are formed as lateral edge flanges from the legs as 29 of the U so that a suitable degree of flexibility is provided as between the opposite guide parts, the width of the space provided between the two guideways 21-22 of the attaching members being slightly less than the distance between the outer edges of the guide parts 23-24, thereby providing for the generation of a strong spring frictional grip of the attaching members upon the body, it being understood that when the attaching members are in position upon the body the connecting portion as 31 of the U will be abnormally bowed by pressure of the attaching members against the legs of the U and that the material of the body is such as to possess an inherent tendency to yieldingly oppose the bowing of the portion 31.

In attaching an eye set as above described within a doll head the set is first positioned with the eye-balls 3-4 arranged within the eye openings of the head and with the attaching members adjacent to the opposing wall surface parts 27-27 of the head. Thereupon the attaching members are slid outwardly along the body to drive the tangs 25 into said wall parts, and the operation is complete.

The doll head illustrated includes, in addition to the parts already described, a pair of rearwardly facing abutments 32-32 arranged adjacent to the wall parts 27-27, being of a character as more fully described and claimed in a co-pending application filed concurrently herewith, file No. M-267. These abutments bear a predetermined relationship, as to position, with respect to the eye openings of the head, and the carrier of the eye set herein described is peculiarly adapted to co-operate with said abutments, particularly, the attaching members of said carrier are shaped to provide broad flat forwardly facing surfaces as 33 in the same vertical plane as the tangs 25 of said attaching members so that said tangs and surfaces may rest against and move along said abutments during the operation of adjusting the carrier to dispose the eyes 3-4 in proper alignment with the head openings.

Engagement of the attaching members of the carrier against the abutments will limit the forward movement of the carrier toward the front wall of the head, and due to the relative positions of the abutments and head openings will determine the degree of flexing of spring 11 in its effort to hold the eyes in proper contact with the rearwardly facing concaved surfaces 12 of the eye openings.

In some instances it is desirable to provide means for holding the body member 10 of the carrier against possibility of objectionable movement after it has been manually adjusted to position the eyes of the set within the head openings and particularly during the time while the attaching members of the carrier are being slid to attaching position. For this purpose the drawing herewith suggests the use of a suitable retaining device carried by the body member and adapted to be engaged directly with the head independently of the attaching members at any time. In the instance illustrated this retaining device is shown to consist of a forwardly projecting tang as 34 provided at one end of the body member and adapted to be impaled into the adjacent abutment 32 of the head.

After the carrier has been manually adjusted to position the eyes within the head openings a slight pressure is applied to force the tang 34 into the material of the abutment, and thereafter the attaching members 18 and 19 of the carrier may be forcefully slid to attaching position without likelihood or deranging the adjustment of the carrier.

While only a single tang as 34 is shown, it will be understood that this is merely exemplary and that any number of tangs may be used, and that they may be arranged at any suitable place or places upon the carrier, or that any other appropriate form of retaining device may be employed as may be preferred.

It will be understood that where tangs as 34 are employed the yieldable mounting of the eyes upon the carrier will enable the carrier to have a sufficient range of bodily movement to impale the tangs without materially disturbing the adjusted relationship of the eyes within the head openings.

The fact that the carrier engages the limiting abutments 32 of the head by its opposite ends which are widely spaced from each other across the region of the eye openings avoids the necessity for extreme accuracy either in the manufacture of the head or the set or in the operation of assembling these parts together, since any slight variation in details of the manufactured product or any slight misadjustment of the set in its assembly with the head will be considerably minimized in their effect upon the fit of the eye-balls within the eye openings.

That is to say for instance that the effect of a slight misplacement of one of the abutments, due to shrinkage or other causes, or a slight inaccuracy of adjustment of one end of the carrier with respect to said abutment, will be reduced approximately 50 per cent in its effect upon the position of the eye-balls, this because of the location of the eye-balls at a point substantially mid-way between the ends of their carrier.

As many changes could be made in this

construction without departing from the scope of the invention as defined in the following claims, it is intended that all matter contained in the above description, or shown in the accompanying drawings, shall be interpreted as illustrative only and not in a limiting sense.

Having thus described my invention, what I claim as new and desire to secure by Letters Patent is:—

1. An eye set comprising a pair of eyes, a carrier for said eyes by which the eyes are oscillatably supported, the carrier comprising a body member and an attaching member slidably mounted thereon into attaching position, the body member being formed of sheet metal bent longitudinally into U cross section thereby rendering the legs of the U yieldable toward each other, and the attaching member slidably engaging the legs of the U and holding said legs flexed toward each other to thereby hold the attaching member against accidental sliding movement.

2. In an eye set comprising a pair of eyes, a carrier for said eyes by which the eyes are oscillatably supported, and attaching members formed as a part of the carrier movable thereon to attach the carrier in position within a doll head, the combination therewith of other means comprised in the set to engage the head for retaining the carrier against movement with respect to the head during movement of the attaching means to attaching position, and said other means comprising a tang provided upon the carrier projecting therefrom intended to be impaled within the material of the head.

3. An eye set comprising a pair of eyes, a carrier for said eyes by which the eyes are oscillatably supported, said carrier having a tang projecting therefrom to be impaled into the material of the doll head to serve as an attaching means for said carrier, and said carrier having other tangs thereon movable with respect thereto in opposite directions away from each other into impaled relation with the material of the doll head along paths in angular relation to the first tang.

In testimony whereof I affix my signature.

SAMUEL MARCUS.
